UNITED STATES PATENT OFFICE.

LOUIS LONG, OF NEW YORK, N. Y.

DEVICE FOR MAKING BEVERAGES, EXTRACTS, AND EMULSIONS FROM NUTS, FRUITS, SEEDS, &c.

1,281,984.

Specification of Letters Patent. Patented Oct. 15, 1918.

Application filed June 17, 1916. Serial No. 104,298.

To all whom it may concern:

Be it known that I, LOUIS LONG, a citizen of the United States, residing in the city of New York, borough of Bronx, county of Bronx, and State of New York, have invented a certain new and useful Device for Making Beverages, Extracts, and Emulsions from Nuts, Fruits, Seeds, &c, of which the following is a specification.

10 This invention is a device for making beverages, fluid extracts, emulsions or solutions from nuts, fruits, seeds, vegetables, cereals, roots, leaves, plants, flowers or analogous products containing edible, medicinal 15 or other valuable constituents.

The device is of simple and economical construction, particularly efficient in operation, and is so compact that it may, if desired, be readily carried about in the pocket 20 or handbag for use when wanted.

Speaking generally, the invention embodies a container or bag for receiving the material to be operated upon, an elongated tubular member for supporting the bag, and 25 means for drawing a portion of the container into the tubular member and adapted to serve other functions hereinafter described.

In the preferred embodiment of the invention, the tubular supporting member has a comparatively large bearing surface at one end, against which the container is provided at its open end with means, specifically apertures, adapted to engage the means employed for drawing the bag within the tubular supporting member. Said means, in its preferred form, embodies a rod provided at one end with a hook, which engages with the apertures in the bag, for closing the bag. The rod is passed through the tubular member, drawing therewith a portion of the bag to such extent that the bag projects to a slight extent beyond the upper end of the tubular member, whereupon the rod is shifted to a position at substantially right angles to the tubular member, slid longitudinally through the apertures in the bag until said apertures are substantially at the center, and said rod is thereafter rotated to twist that portion of the bag interiorly of the tubular member to draw a further portion of the bag thereinto

for the purpose of compacting the material contained in the bag. This having been accomplished, the bag is introduced in a cup or other vessel containing a small quantity of fluid, say water, sufficient to moisten the contents of the bag, and the tubular supporting member, with the bag maintained more or less tightly in engagement therewith, may be operated in the manner of a pestle, for the purpose of pulping, macerating or squeezing the material within the bag and freeing the same of the oils, juices, or other edible material contained therein.

Features of the invention, other than those specified, will be apparent from the following description, read in conjunction with the accompanying drawing.

In the accompanying drawing, I have illustrated one practical embodiment of the invention, but the construction shown therein is to be understood as illustrative, only, and not as defining the limits of the invention.

Figure 1 is a sectional view showing the supporting member and bag assembled in cooperative engagement and positioned within a cup containing a liquid, said cup being also shown in central section.

Fig. 2 is a side elevation of the preferred form of bag in condition to receive the material to be operated upon, and

Fig. 3 shows the relation of the parts after the material has been placed within the bag, and the bag and rod assembled for inserting the same through the passage of the tubular supporting member.

Referring to the drawings, A designates a flexible container shown in the form of a bag, which may be made of canvas or any other suitable flexible material having the required strength. Near the open end of the bag A is a plurality of apertures *a*, and, after the material *x* to be treated has been positioned in the bag, the bag is folded, as shown in Fig. 3, to bring all the apertures in registration or alinement with one another.

B is a rod, provided at one end with a hook *b*, and at its other end with a loop *b'*. When the bag has been folded, as described, the hook *b* is passed through all of said apertures, after which the assembled rod and bag are brought into the position sub-

stantially as shown in Fig. 3, to be passed through an elongated passage *c* of a supporting member *C*. The supporting member *C* may partake of various forms, but it is herein shown as a tubular member through which the elongated passage *c* extends, and the outer contour of which tubular member is formed or configured so as to serve, more or less, as a hand-grip, and particularly in conjunction with rod *B*, for operating as described.

After positioning the parts, as shown in Fig. 3, rod *B* is passed through passage *c* of the tubular member to such extent that the enlargement or loop *b'* may be grasped from the other end of said passage, whereupon the rod is drawn through the passage, pulling bag *A* after it, until apertures *a* of the bag reach a point slightly above the upper end of the hand-piece or supporting member *C*, whereupon the rod is shifted to a position at right angles to the longitudinal axis of the supporting member and subsequently slid through apertures *a* until said apertures engage with the rod substantially central of its length.

The rod may now be rotated, if desired, to twist that portion of the bag which extends through passage *c* and this twisting operation will draw further portions of the bag into said passage. The twisting operation continues until a sufficient portion of the bag has been drawn within the passage *c* for the purpose of drawing the bottom of the bag more or less taut around the material being treated.

The material-containing portion of the bag, mounted as described on tubular member *C*, is next immersed in a small quantity of liquid *d* contained within a suitable vessel, such as a cup *D*, as shown in Fig. 1. The liquid referred to may be water, or any other suitable menstruum, and may be heated or not, as desired. The construction or formation of tubular member *C* is such that, when in the position described, the upper end of it may be grasped by the hand and operated as a pestle to grind, pulp or press the material against the bottom and sides of cup *D*, which latter thus serves the functions of a mortar. The lower end of member *C* is provided with a relatively large bearing surface *c'*, whereby cutting of the bag is precluded during the macerating or squeezing operations. The operations just described disrupt the cells of the material treated and cause an exudation of the desired constituents through the walls of the bag, and, of course, in solution or emulsion with the water or other menstruum. During the use of the device as a pestle, inadvertent unwinding of rod *B* is precluded by two oppositely positioned depressions *c'* formed at the upper end of supporting member *C*, in which rod *B* may be seated.

After the macerating or pulping operations are concluded, rod *B* may be rotated to draw a further portion of the bag into passage *c*. This operation serves to pull the material-containing portion of the bag against the enlarged bearing or compressing surface *c'* of member *C*. The portion of the bag containing the material is thereby compressed or squeezed, with the result that the extracted material is forced out of the bag and into the liquid within the cup. The macerating and squeezing operations may be repeated as desired, until the material is thoroughly extracted.

At the conclusion of the macerating or pulping operations, rod *B* may be grasped and, either by a direct pull or by rotary movement, operated to draw a further portion of the material-containing portion of the bag into passage *c'*, for the purpose of tightly compressing the material to completely squeeze out the residuary liquid into the cup. If the rod is operated to twist the bag, a wringing effect is exerted on the bag, thereby facilitating the separation of the liquid from the bag.

It will be understood that the material treated may be any one or a combination of a large number of products, such, for example, as nuts, fruits, seeds, vegetables, cereals, roots, leaves, plants, flowers, herbs, etc., and that the resulting liquid may be a beverage, an extract or a medicinal preparation.

In the foregoing description, the container or bag *A* has been specifically described as a canvas or other fabric bag, and, when operating with a bag of this character, only the juices or liquid content of the material operated upon will pass through the wall of the bag and intermix with the liquid *d*. It will be understood, however, that the bag may be formed from a fine mesh or from a comparatively loosely woven fabric. Container *A* has been herein described as a bag, but it will be understood that, if desired, a sheet of material, the corners of which may be caught up, may be employed. Moreover, when a bag is used, it is stretched more or less during use, and, in order to compensate therefor, the bag may be provided with an additional set of apertures *a'*, as shown in Figs. 2 and 3. Various other slight modifications in structural details will be apparent to those skilled in the art in adapting the invention to its various environments, without departing from the spirit of the invention. Accordingly, the invention is to be understood to be as broadly novel as is commensurate with the appended claims.

The material operated upon may be treated in various ways so as to produce the desired solution after operation; that is to say, the nuts or seeds may be roasted or

properly cut or conditioned for subsequent operation within the bag.

Having thus fully described the invention, what I claim as new, and desire to secure by Letters Patent, is:

- 5 1. A device of the class described embodying an elongated tubular support, a container for receiving the material to be operated upon, an elongated rod provided at one end with a hook-shaped member adapted to engage with the container for introducing a portion of the container into the interior passage of the support to such extent that a portion thereof extends beyond
- 10 15 the opposite end of the support, said rod being subsequently shiftable to a position wherein a portion of the rod intermediate its ends will engage with the container, and being thereafter rotatable to twist the portion 20 of the container extending interiorly of the support for the purpose of drawing a further portion of the container thereinto, whereby the material within said container is compressed.
- 25 2. A device of the class described em-

bodying an elongated tubular support, a flexible bag for receiving the material to be operated upon, and provided near its open end with a plurality of apertures, an elongated rod formed at one end with a hook-shaped member adapted to be passed through said apertures for closing the open end of the bag and subsequently introducing a portion of said bag into the interior passage of the support to such extent that a portion thereof extends beyond the opposite end of the support, said rod being then shiftable to a position wherein the apertures of the bag engage with the rod substantially central of its length, and said rod being thereafter rotatable to twist the portion of the bag extending interiorly of the support for the purpose of drawing a further portion of the bag thereinto, and the support thereafter operated as a pestle to pulp or mace- 45 rate said material.

In testimony whereof I have signed my name to this specification.

LOUIS LONG.
